CLAIM

The ornamental design for an electroacoustic transducer, as shown.

DESCRIPTION

FIG. 1 is a perspective view of the top, front and right of an electroacoustic transducer showing my new design;

FIG. 2 is a perspective view of the bottom, front and right side thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.
